UNITED STATES PATENT OFFICE.

CHARLES W. STEVENS, OF SIDNEY, IOWA.

RAILROAD-SPIKE.

No. 906,079.

Specification of Letters Patent.

Patented Dec. 8, 1908.

Application filed December 4, 1905. Serial No. 290,197.

To all whom it may concern:

Be it known that I, CHARLES W. STEVENS, a citizen of the United States, residing at Sidney, in the county of Fremont, State of Iowa, have invented certain new and useful 5 Improvements in Railroad-Spikes; and I do hereby declare the following to be a full, clear, and exact description of the invention, such as will enable others skilled in the art to which it appertains to make and 10 use the same.

This invention relates to railroad spikes and has for its object to provide a spike which when driven into a railroad tie will be securely held therein, thereby preventing 15 displacement of the rails.

With the above and other objects in view, the invention consists in the construction and arrangement of parts shown in the accompanying drawings, in which:

Figure 1 is a front elevation of the spike. Fig. 2 is a side elevation. Figs. 3 and 4 are detail horizontal sectional views on the lines 20 3—3 and 4—4 of Fig. 1. Fig. 5 is a rear elevation of the spike.

Referring to the drawings, the numeral 5 denotes the shank of the spike, 6 the head of the same and 7 the toe or point.

Formed on the front face of the shank 5 of the spike and at its point of junction with the head 6 is a lug 8 which is rounded as at 30 9 at one side, the said rounded portion being formed by omitting a portion of the front face of the lug and a portion of one of the 35 side faces of the same.

Formed on each of the side faces of the shank 5 intermediate the head 6 and the toe 7 is a series of ribs 10 and 10'. Each rib of the series 10 and 10' has its ends flush 40 with the front and rear faces of the shank and each has a horizontal under face 11 and an inclined top face 12, the inclined face of each series lying in different planes. The front face of the shank has an angular edge 45 13 and a rounded edge 14, the rounded edge 14 being located on the opposite side of the shank to the rounded edge 9 of the lug 8 and the rear face of the shank including an angular edge 15 and a rounded edge 16, the 50 rounded edge 16 being on the same side of the spike as the rounded edge 9 of the lug 8, resulting in each of the side faces of the shank including an angular edge and a rounded edge. The ribs 10 and 10' are as 55 stated rounded at one of their ends to con-

form to the contour of the corresponding rounded edge of the shank.

The lower end portion 7 of the spike has the shape of a spear-head somewhat, two of the side faces thereof being vertical and parallel 60 while the other two side faces 16' and 17 converge downwardly to a cutting edge. At the upper ends of the side faces 16' and 17 are the shoulders 18 which are respectively parallel with the upper faces of the ribs 10 65 and 10' next above.

In practice, the spike is driven into the tie with one of the two series of ribs facing the rail. After being driven almost the entire distance, the spike is given a 70 quarter of a turn to bring the head into proper engagement with the rail flange, the ribs 10 and 10' serving to tighten the contact of the head with the said flange. The spike is, of course, turned in the direction of curvature of the ribs and the lug 8 and the angular edges of the said ribs and lug prevent 75 accidental return of the spike to its position before it was turned.

What is claimed is:

1. A spike having its shank formed with diagonally opposite angular corner edges, and oppositely disposed rounded edges, and a lug formed upon the shank, said lug having a rounded edge presented in the direction of rotation of the spike when driven 80 into a body and the angular edge presented in an opposite direction.

2. A spike comprising a shank, series of threads formed on opposite faces of said shank, each of said threads having a horizontal under face and an inclined top face resulting in a cutting edge and a shouldered edge.

3. A spike comprising a shank formed 90 with oppositely disposed flat sides and oppositely disposed rounded sides, each of said rounded sides being merged into one of the flat sides, and threads formed upon each of said rounded sides, the said threads 95 being each extended entirely across the rounded side upon which it is formed and throughout the merged face portion of the said merged side.

In testimony whereof, I affix my signature, in presence of two witnesses.

CHARLES W. STEVENS.
